UNITED STATES PATENT OFFICE

EDGAR F. HATHAWAY, OF WELLESLEY, MASSACHUSETTS, ASSIGNOR TO SHAWMUT ENGINEERING COMPANY, OF DORCHESTER, MASSACHUSETTS, A CORPORATION OF MASSACHUSETTS

TUFT YARN CARRIER OR TUBE-FRAME

Application filed November 7, 1928. Serial No. 317,728.

My present invention relates to the handling of threads or yarns and particularly tuft yarns for moquette or other pile fabric looms, such as Axminster carpet looms, and aims to provide an improved and simplified means for supporting and presenting spooled tuft yarns in the course of weaving. As to all common subject matter this application is a continuation in part of my copending application Serial No. 290,916, filed July 7, 1928.

In the drawings illustrating certain embodiments of the invention

Fig. 1 is a front elevation of one end of a yarn carrier or "tube frame" with supported yarn spool;

Fig. 2 is a vertical section transversely through the carrier and spool of Fig. 1, showing also a portion of a yarn engaging instrumentality of the loom in position about to engage a yarn;

Fig. 3 is a bottom plan of the carrier as in Fig. 1;

Figs. 4 and 5 are respectively perspectives of a single yarn-spacing and gripper-guiding member such as illustrated in Figs. 1 to 3, and a section of an attaching element or strip therefor; and

Figs. 6 and 7 are respectively a vertical cross-section through a modified form of carrier, and a plan of a portion thereof.

Referring more particularly to the drawings and first to Figs. 1 to 5, the tuft yarn carrier or "tube frame" as illustrated comprises a frame 1 or main longitudinal supporting element, shown as a tubular metallic member but which may be of other material or otherwise formed, for instance, as a wooden bar. Said frame or carrier proper is of a length to support along it one or more tuft yarn spools, as required, a portion of one spool being shown at 2. The spool is rotatably supported upon the frame as by means of the bearing member 3 receiving the spool pintle 4, similar means being provided at the opposite end of the frame, and at an intermediate point or points where a plurality of spools are to be supported. The frame is adapted for connection with the carrier chain of the loom in any desired or usual manner as by means of the chain engaging member 5 and

the hook-latch 6 provided at each end of the carrier frame.

The series of yarns or yarn units 7 extend from the spool 2 upon which they are wound across one face of the frame 1, that at the left as viewed in Fig. 2. For convenience in description this side or face of the frame, across which the yarn ends extend, will be referred to as the frame front, while the face or portion of the frame at an angle thereto and below it will be referred to as the under portion or bottom of the frame.

Along one face of the frame, the bottom face as herein illustrated, is provided yarn spacing and gripper guiding means herein comprising a longitudinal series of guide members, guides or barriers 9 illustrated as metallic strip-like devices or bars distributed along the frame in edgewise relation to it and each with one end extending outwardly beyond the bottom face of the frame, at the side across which the yarns 7 extend.

Suitable means is provided for attaching said yarn-spacing and gripper-guiding means to the frame 1. Herein for the purpose there is illustrated a longitudinal element or attaching strip 10, best seen in Fig. 5, having at suitable intervals apertures 11 for receiving a fastener such as the screw or bolt 12, Fig. 2, extending through corresponding openings 80 in the adjacent face, herein the bottom face, of the frame 1 and removably engaging the opposite frame wall as by means of the lock-nut 13. The edge of the fastener-receiving apertures 11 of the attaching strip may be 85 up-set as indicated at 14, Figs. 2 and 5 to insure accurate positioning of the attaching strip upon the frame.

Said attaching strip 10 as illustrated is formed with a depending flange 15 which, 90 together with the adjacent portion of the strip, if desired, has a series of formations such as slots, notches, perforations or the like 16, each adapted to receive one end, herein the inner end, of one element or member 9 95 of the spacing and guiding means. The inner ends of said members or guides 9 are adapted to be received in said formations 16, preferably with a slightly loose fit, and as shown are formed each with a tongue 17 for reception in 100

the corresponding formation 16 of the attaching strip 10.

Along a portion of the attaching strip spaced from the flange 15 additional means 5 for positioning and holding the yarn-spacing and gripper-guiding members or guides preferably is provided. Said means as herein illustrated is of relatively small height as compared with the flange 15, being in the 10 form of a hollow or approximately U-shaped rib 18 bent or struck up from the body of the strip 10 and preferably rounded substantially as illustrated. Said rib 18 is formed with a series of slots, notches or the like 19 registering with the formations 16 of the strip flange and of a width to receive each a guide 9, also preferably with a slightly loose fit, said rib thus comprising in effect a series of spaced straps or eyes aligned lengthwise of the strip. 15 20 The guides 9 are assembled with the attaching strip 10 so that an intermediate portion of each guide lies in a slot or recess 19 of the rib 18 and an end portion, herein the inner one, is received in the corresponding slot, 25 notch or other formation 16 of the flange 15. To hold or lock said guides in assembled position suitable means is provided, such as the locking pin or bar 20 adapted to be passed through and beneath the rib 18 and through a 30 locking formation or aperture 21 provided for the purpose in each guide.

At the outwardly extending ends of the guides 9 means is provided whereby the respective yarn units will be retained in properly spaced feeding position, one between each two adjacent guides, said means being arranged to permit broadside threading or positioning of the yarns in said relation, when desired. In the present embodiment of the 35 invention each guide 9, as best seen in Figs. 1, 3 and 4, accordingly has formed at or near its outer end portion a locking device or laterally deflected barb-like nib 22 having an inwardly inclined forward or outer edge, as indicated at 23. The nib 22 of each guide 9 projects above and to or across that of the next adjacent guide, but spaced sufficiently from it to permit a yarn unit to be entered past the nib in a broadwise manner, being 40 guided into position by the nib and the adjacent guides. After being entered beyond the nib, a yarn unit is located and retained positively against reverse escape in the yarn passage 24, see particularly Figs. 3 and 4, between 45 the inner edge of the nib and the carrier frame.

Said passages 24, as herein illustrated, are further defined by means of additional offsets or shoulders 25 formed on the guides 9 and cooperating with the nibs 22 and with the adjacent portions of the guides 9 to provide a substantially completely surrounding wall for each yarn passage 24, see particularly Fig. 3, in which its yarn unit will be positively 50 retained yet into which the yarn may be

entered in a broadside fashion. Accidental lengthwise withdrawal or slipping back of the yarn may be retarded or prevented by forming either the nibs 22 or shoulders 25 or both, as shown, at their opposite under edges 70 with depending and slightly converging burrs, lips or the like as indicated at 26 upon the nibs and at 27 upon the shoulders. While the yarns may feed freely downward between said formations 26 and 27, the latter will 75 engage the yarn fibres and prevent upward retraction of the yarns.

It will be understood that in the weaving operation an instrumentality of the loom, such as the nipper or grippers G shown in 80 part in Fig. 2, is entered into and guided in each inter-guide space to engage or grasp the yarn therein, to draw it into the warp. By giving the guides 9 a somewhat loose fit in their supporting means, herein the strip 10 as previously described, the resulting slight play affords a certain flexibility in the co-operation of the grippers with the guides, allowing the latter to adjust themselves to 85 the noses of the grippers in case any of the latter should tend to catch or bind while being inserted or withdrawn. The shoulders 25 on the guides are also useful in this connection, acting as stops or guides for the inner ends of the grippers and further insuring their proper engagement with the adjacent yarns, as does also the adjacent rounded portion of the rib 18 of the attaching strip.

It will be further noted that the yarns 100 may feed freely down through and between the several guides 9, the space between the latter being entirely free and unobstructed by the attaching strip or otherwise substantially from the outer ends of the guides to 105 their opposite ends, and below the yarn retaining nibs 22 and shoulders of the guides 25 and the shallow rib 18 of the attaching strip 10. Also the guides 9 preferably are markedly recessed or cut away at one or both 110 long edges, as illustrated at 28 in Figs. 2 and 4.

In Figs. 6 and 7, in which parts not otherwise mentioned may be similar as in preceding figures, the vertical yarn passages and 115 the means for retaining the yarns therein while permitting their broadside reception are formed integrally with the barriers or guides 9" as in the form of Figs. 1 to 5. In this instance the upper forward portion of 120 each of said guides 9" is recessed or stamped out, substantially as illustrated, to form a reversely extending finger or nib 35 which is also laterally deflected, in a sinuous manner, as clearly seen in Fig. 7. The inner end 125 of each of the fingers 35 extends across to and above the recess in the adjacent guide 9" thus barring a yarn positioned in the passage 36 against escape outwardly unless intentionally bent out around the inner end of 130

the finger. In the opposite or threading direction, however, the yarns may readily be entered into the respective passages 36 broadwise.

5 Having thus described certain illustrative embodiments of my invention it will be understood that the invention is not limited to the particular means shown and described herein, its scope being set forth in the following claims:

1. In a tuft-yarn carrier or tube-frame for looms, a frame, and a series of transverse barriers or guides therealong adapted to receive yarns between them and to guide loom 15 grippers in engaging the yarns, and broadside-threadable, substantially rigid yarn locking devices formed respectively as parts of the individual barriers or guides, such locking device for each guide extending 20 across to the next adjacent guide and cooperating therewith to retain a yarn.

2. A yarn-spacing and gripper-guiding member comprising a strip-like main portion or bar adapted for edgewise attachment 25 to a tuft-yarn carrier or tube-frame, laterally deflected portions at one end thereof spaced to provide a yarn passage between them, the outer of said deflected portions having an inwardly inclined outer edge to 30 guide a yarn unit to said passage, an attaching portion at the opposite end of said member, and an intermediate securing formation.

3. A yarn-spacing and gripper-guiding member for use with tuft-yarn carriers or 35 tube-frames, comprising a flat metallic body, a laterally deflected yarn-retaining element on one end portion, the opposite end portion being adapted for engagement with a holding means of the frame, and an intermediate locking formation on said member.

4. Guide-attaching means for tuft-yarn carriers or tube-frames, comprising a metal strip, a longitudinal flange on said strip having a series of guide-receiving formations, and a hollow longitudinal rib adapted 45 for sliding reception of a guide-locking pin, said rib being spaced from said flange toward the yarn side of the carrier or frame, being of less height than the guides to be attached and having a series of guide-receiving formations in registry respectively with those of said flange, and means for attaching said strip to a frame.

5. A yarn spacer and gripper guide for a 55 tuft-yarn carrier or tube-frame, comprising an elongated main portion or body, a laterally deflected nib at one end portion, a lateral projection or shoulder cooperable with said nib to receive a yarn unit between them, and 60 a locking formation at a longitudinally intermediate part of said main portion or body, the other end portion of the guide being constructed and arranged for reception by a holding means of a frame.

6. A yarn spacer and gripper guide for a

tuft-yarn carrier or tube-frame, comprising an elongated main portion or body, a laterally deflected yarn-retaining element on one end portion, and a locking formation at a longitudinally intermediate part of said main 70 portion or body, the other end portion of the guide being constructed and arranged for reception by a holding means upon the frame.

7. Guide-securing means adapted for attachment to a tuft yarn carrier or tube-frame, 75 comprising a strip having a flange at an angle therewith, a series of notches, slots or like guide-receiving formations along said flange, and a hollow and relatively shallow rib projecting from said strip at the same face as 80 said flange, having a correspondingly spaced series of guide-engaging formations and adapted to receive within it a pin for interlocking the guides with the strip.

8. In a tuft-yarn carrier or tube-frame for 85 looms, a frame, spool supports thereon, a series of transversely extending guides adapted to receive yarns between them and to guide grippers of a loom in engaging the yarns, broadside-threadable yarn-spacing and retaining means associated with said guides, and means for securing said guides to the frame, comprising a longitudinal strip, a flange therealong at an angle to the strip body, a series of guide-receiving formations 90 along said flange, a second and registering series of guide-engaging formations, of less height than the guides, and spaced from the latter, said last mentioned guide-engaging formations comprising a multiplicity of 95 straps or eyes aligned longitudinally of the strip and adapted to receive and support a guide-locking pin.

9. A yarn-spacing and gripper-guiding member for use with tuft-yarn carriers or 100 tube-frames, comprising a flat metallic body, a laterally deflected yarn-retaining element on one end portion, the opposite end portion and an intermediate portion being respectively adapted for engagement by holding 105 means on the frame.

10. In a tuft-yarn carrier or tube-frame for looms, an element extending along the carrier, having its major transverse axis substantially perpendicular to the plane of the 110 yarns, and projecting sufficiently at the front or yarn face of the carrier to separate yarn-units extending across that face, said element comprising a series of yarn-unit spacing formations, each accessible to said yarn-units 115 broadwise of the latter and having deflected portions for positively retaining the yarn-units in their respective spaced positions.

11. In a tuft-yarn carrier, a substantially rigid longitudinal element at one face of the 120 carrier for separating the yarns, said element formed with a lengthwise series of transverse rib-like members spaced to provide entrance passages between each two adjoining members, for broadside reception of the yarns, 125 130

and formed with a corresponding series of deflected yarn-retaining portions.

12. In a tuft-yarn carrier, a longitudinal element at one face of the carrier for separating the yarns and guiding grippers of a loom, said element comprising a lengthwise series of yarn-receiving formations having entrance passages for broadside reception of the yarns, a yarn-retaining member projecting transversely of each formation, and a series of yarn-separating gripper guide portions cooperating with said formations and said members positively to retain the yarns against broadside escape.
13. In a tuft-yarn carrier, a frame, broadside-threading yarn-spacing gripper-guides in longitudinal series along the frame, a corresponding series of intermediately projecting substantially rigid devices for positively retaining the positioned yarns, said devices formed on said guides and each extending from its supporting guide into overlapping relation with the next adjacent guide, and a longitudinal attaching strip for said means.
14. In a tuft-yarn carrier, a frame, broadside-threading yarn-spacing gripper-guides in longitudinal series along the frame, and a corresponding series of intermediately projecting substantially rigid devices for positively retaining the positioned yarns against broadside escape, said devices formed on said guides and each extending from its supporting guide into overlapping relation with the next adjacent guide.
15. In a tuft-yarn carrier for looms, a frame, transverse wall-forming devices therealong, each such device constituting both a yarn spacing and a gripper guiding means, and associated substantially rigid means extending laterally from each device into overlapping relation with the next device and arranged to permit broadside threading of the yarns between said devices but adapted to retain the yarns against reverse displacement.
16. In a yarn carrier or frame for looms, in combination with a main frame, an element along and secured to the frame for guiding the yarn-grippers of a loom and also to space the yarns, said element comprising a plurality of transverse rib-like members positioned to guide the yarn-grippers between them and projecting at one face of the frame to receive yarns in a broadwise manner between their projecting portions, each such member having a bar-like laterally deflected yarn-retainer formed on its projecting portion.
17. In a yarn carrier or frame for looms, a gripper-guiding and yarn-spacing device comprising a rib-like metallic element having formed at an edge portion of one end part a laterally deflected broadside-threadable yarn-retainer.
18. In a yarn carrier or frame for looms,

a gripper-guiding and yarn-spacing device comprising a rib-like metallic element having formed at one end portion a laterally deflected broadside-threadable yarn retainer.

19. In a yarn carrier or frame for looms, a gripper-guiding and yarn-spacing device comprising a rib-like metallic element having formed at one end portion a laterally deflected broadside-threadable barb-like yarn-retainer having an inclined yarn-guiding edge.

20. A tuft yarn frame comprising a body bar provided with means for carrying a tuft yarn spool, a row of laterally spaced and laterally movable plates forming passages between them for yarn strands delivered from said spool, means connecting said bar and said plates, and means maintaining said plates in yarn-spacing predetermined positions while permitting them to yield laterally.

21. A tuft yarn frame comprising a body bar provided with means for carrying a tuft yarn spool and having a part provided with laterally spaced openings therein, a row of laterally spaced plates within said openings and forming passages between them for yarn strands delivered from said spool, said openings being wider than said plates and permitting lateral movement of the plates therein, and means to retain said plates within said openings while permitting them to yield laterally therein.

22. A tuft yarn frame comprising a body bar provided with means for carrying a tuft yarn spool and having a part provided with laterally spaced openings therein, a row of laterally spaced plates within said openings and forming passages between them for yarn strands delivered from said spool, said openings being wider than said plates and permitting lateral movement of the plates therein, and a removable rod penetrating said part and said plates and holding them in operative relationship.

23. A tuft yarn frame comprising a body bar provided with means for carrying a tuft yarn spool and having spaced parallel parts projecting therefrom and extending longitudinally thereof, each of said parts having a row of openings therein alined with the openings of the other part transversely of the bar, a row of laterally spaced and laterally movable plates forming passages between them for yarn strands delivered from said spool and extending between said parts and into the openings therein, and means to retain said plates in laterally movable position within said openings.

24. A tuft yarn frame comprising a body bar provided with means for carrying a tuft yarn spool and having spaced parallel parts projecting therefrom and extending longitudinally thereof, each of said parts having a row of openings therein alined with the open-

ings of the other part transversely of the
bar, a row of laterally spaced and laterally
movable plates forming passages between
them for yarn strands delivered from said
spool and extending between said parts and
into the openings therein, and a common
means cooperating with one of said parts and
holding said plates in operative relationship.

In testimony whereof, I have signed my
name to this specification.

CERTIFICATE OF CORRECTION.

Patent No. 1,914,916.

June 20, 1933.

EDGAR F. HATHAWAY.

It is hereby certified that error appears in the printed specification of the above numbered patent requiring correction as follows: Page 4, line 56, claim 16, for "bar-like" read "barb-like"; and that the said Letters Patent should be read with this correction therein that the same may conform to the record of the case in the Patent Office.

Signed and sealed this 22nd day of August, A. D. 1933.

M. J. Moore.

Acting Commissioner of Patents.
